CIGARETTE PACKAGE

James E. Shouse, Louisville, Ky.

Application August 25, 1936, Serial No. 97,805

3 Claims. (Cl. 229—44)

This invention appertains to new and useful improvements in paper receptacles, and more particularly to a novel cigarette package, or package for other contents.

5 The principal object of the present invention is to provide a cigarette package which can be conveniently opened and equally as conveniently closed.

Another important object of the invention is 10 to provide a cigarette package which can be quickly snapped open so that a cigarette can be extracted.

Still another important object of the invention 15 is to provide a cigarette package constructed of a single sheet of material so assembled as to incorporate a closure and means for operating the same.

These and various other important objects and 20 advantages of the invention will become apparent to the reader of the following specification.

In the drawings:—

Figure 1 represents a perspective view of the package.

Fig. 2 represents a side elevational view of the 25 package with the closure in open position.

Fig. 3 is an enlarged fragmentary vertical sectional view on line 3—3 of Fig. 2.

Fig. 4 is an enlarged fragmentary vertical sectional view on line 4—4 of Fig. 1.

30 Fig. 5 is a fragmentary vertical sectional view showing the closure in open position.

Fig. 6 is an enlarged fragmentary sectional view on line 6—6 of Fig. 1.

Fig. 7 is a fragmentary horizontal sectional view on line 7—7 of Fig. 5.

Fig. 8 represents a plan view of the blank.

Referring to the drawings wherein like numerals designate like parts, it can be seen in Fig. 8, that numeral 5 generally refers to the 40 paper blank. It is preferable that the paper be rather stiff and is cut to provide an elongated rectangular piece, capable of being bent on the lines a—b to define the side walls 6—7 and the end wall 8 and also capable of being bent on the 45 lines c—d to define the overlapping end wall sections 9—9.

At the upper edges of the side walls 6 and 7 short flaps 10 and 11 are provided adjacent the end wall sections 9. A closure flap 12 comprising an elongated tongue 13 extends from the upper edge of the end wall 8. All this construction is integral. The flap 12 is provided with a longitudinally extending reinforcing rib or depression 14 and additional reinforcing ribs 15 are 55 provided along the sides 6—7 and the end wall

8. The upper portion of the end wall 8 is provided with an outwardly bulged button 16, which at its upper end is connected to the closure flap 12 in a manner and for a purpose to be described in detail. 5

The upper edge portions of the side walls 6—7 as well as the end wall sections 9—9 are provided with narrow marginal portions 17 which are bent inwardly and made arcuate as shown in Fig. 5.

Elongated bottom forming flaps 18 are provided 10 along the lower edge of the side walls 6—7, wall 8 and end wall sections 9—9 and these are creased as along the lines 19 so as to form the bottom for the package.

The package is formed by bending on the lines 15 a to d inclusive, bringing the end wall sections 9—9 into overlapping relation and then secured together as by adhesive. The flaps 10—11 are folded together one over the other and then secured together in the same manner. 20

The free end portion of the flap 12 is bent upon itself to form a tongue 21 on the under side thereof and a finger grip tab 22 in advance of said tongue. The tongue 21 is designed to be inserted in a slot 20, formed in the flaps 10 and 11, to 25 lock the flap 12 in closing position in a manner presently referred to in detail.

Reverting to the flap 12 and button 16, these parts are so arranged that the flap 12 is hinged at its rear corners, as at 12', to the upper rear 30 corners of the side walls 6 and 7 for swinging movement thereon into opening and closing positions. The button 16 is flexible inwardly and reactive outwardly and comprises a top part 16' forming a rearwardly extending lever portion on 35 the flap 12 on the opposite side of the axis of movement of the flap, whereby under inward flexing of said button, as by thumb or finger pressure, the top, or lever portion, 16' exerts a leverage in one direction on the flap 12 to swing the 40 same into opening position. Conversely under outward reaction of said button 16 leverage is exerted in the opposite direction by said portion 16' to close said flap 12.

The tongue 21 is inclined in the proper direction, i. e., toward the axis of movement of the flap 12, to facilitate insertion thereof in the slot 20 and its removal therefrom under swinging movement of said flap, said tongue frictionally coacting with the slot to hold the flap 12 closed. 45 50

The inwardly bent arcuate portions 17 of the side walls 6 and 7 receive the side edges of the flap 12 therebetween and prevent the latter from buckling outwardly in its closed position. As will be understood the portions 17 are adapted to be 55

bulged outwardly under pressure exerted against the end wall 8 and end wall sections 9 to thereby release the flap 12.

It is to be understood that the package can be made of tin or other flexible material suitable for the purpose.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

- 15 1. A container comprising top, side and end walls, respectively, of relatively stiff flexible material, the top wall having an opening therein, a closure flap for said opening having rear corners hinged to the upper corners of said side walls adjacent one end wall, said end wall having formed integrally therewith an inwardly flexible outwardly reactive button including a top part forming a lever-like rear extension on said flap on the relatively opposite side of the axis of movement of the flap whereby under flexing and reaction of said button the flap is swung to opening and closing positions respectively.
- 20 2. A container comprising top, side and end walls, respectively, of relatively stiff flexible material, the top wall having an opening therein, a closure flap for said opening having rear corners hinged to the upper corners of said side walls adjacent one end wall, said end wall having
- 25
- 30

formed integrally therewith an inwardly flexible outwardly reactive button including a top part forming a lever-like rear extension on said flap on the relatively opposite side of the axis of movement of the flap whereby under flexing and reaction of said button the flap is swung to opening and closing positions, respectively, said top wall having a slot therein in advance of the opening, and said flap having a tongue thereon insertable into said slot to frictionally lock the flap in closing position, the tongue being inclined from the slot toward the axis of movement of the flap to facilitate its removal from said slot.

3. A container comprising top, side and end walls, respectively, of relatively stiff flexible material, the top wall having an opening therein, a closure flap for said opening having rear corners hinged to the upper corners of said side walls adjacent one end wall, said end wall having formed integrally therewith an inwardly flexible outwardly reactive button including a top part forming a lever-like rear extension on said flap on the relatively opposite side of the axis of movement of the flap whereby under flexing and reaction of said button the flap is swung to opening and closing positions, respectively, the side walls being provided with concave marginal edges receiving the flap therebetween in the closing position of the latter to prevent the same from flexing outwardly, said marginal edges bulging outwardly under pressure exerted against the end walls to thereby free said extension.

JAMES E. SHOUSE.
